UNITED STATES PATENT OFFICE.

ARNOLD CHRISTIANSON, OF DETROIT, MICHIGAN.

MILL FOR ROLLING TAPERED DISKS.

1,399,334.

Specification of Letters Patent.

Patented Dec. 6, 1921.

Application filed July 21, 1920. Serial No. 397,957.

To all whom it may concern:

Be it known that I, ARNOLD CHRISTIANSON, a resident of Detroit, in the county of Wayne and State of Michigan, have invented 5 a new and useful Improvement in Mills for Rolling Tapered Disks, (Case 2,) of which the following is a specification.

The invention relates to rolling apparatus designed particularly for converting metallic cup shaped blanks into disks of decreasing thickness from near their centers to their peripheries.

In my application of even date herewith, Serial No. 397,958, is described a method 15 of forming disks for steel wheels, such as used on motor cars, which are of decreasing thickness from near their centers to their peripheries; said method consisting in taking a circular metal plate, forming it into a 20 deep cylindrical metal cup, preferably by punch-drawing through a die or succession of dies, and then subjecting the walls of the cup to a rolling action applied circumferentially thereof, and giving the greatest 25 reduction at the open end of the cup and gradually decreasing toward its bottom, thereby expanding the blank circumferentially, progressively through different stages 30 of flare, to a substantially flat disk which tapers from near its center to its periphery.

The apparatus of this application is one form for converting such cup shaped blanks into disk form.

In the accompanying drawings Figure 1 35 is a plan view of the machine; Fig. 2 is a central longitudinal vertical section thereof; and Fig. 3 is a transverse section on the line 3—3, Fig. 1.

In the drawings 1 indicates a cup-shaped 40 blank, preliminarily flared, for reducing to disk form. 2 and 3 are spinning rolls, preferably of conical form as shown and mounted in suitable bearings with their axes converging so as to permit both rolls to enter 45 the cup-shaped blank. These rolls are so mounted that the angle between their axes can be progressively increased. As shown the respective shafts of said rolls are mounted in bearings 4 and 4^a on carriers 5 and 5^a, 50 respectively, which carriers are pivotally secured to the main frame 6 at 7 and 7^a respectively. The outer end of each carrier is provided with an inwardly projecting portion 8 extending underneath and outwardly projecting portion 9 of the main frame, in order to prevent the outer ends of the carriers from rising. Attached to

the two roll carriers are rack bars 10 and 10^a, which are formed on an arc struck from the centers 7 and 7^a of the respective roll carriers. These rack bars are engaged respectively by pinions 11 and 11^a, journaled on vertical axes in the main frame, one slightly higher than the other, but with the lower portion of pinion 11 meshing with the upper portion of pinion 11^a. The rack bar 10 is engaged by the upper portion of pinion 11 and the rack bar 10^a by the lower portion of pinion 11^a. The axis of pinion 11 is extended upwardly as a shaft 12 provided with a hand wheel 13, so that by rotating said hand wheel the two pinions 11 and 11^a are rotated in opposite directions and consequently move the rack bars 10 and 10^a, and the roll carriers to which the latter are attached, in opposite directions.

The cup shaped blank will be provided with a central opening in its bottom for receiving a fastening member 15 whose shank extends through said opening and secures the cup to the plate or disk 16. The latter is provided with a shaft mounted in bearings 17 and with suitable driving means, such as a pulley 18 adapted to receive a belt coming from any suitable source. The bearings 17 are carried on the upper ends of standards 19 rising from a carriage 20 mounted in suitable ways 21 in the main frame so as to move longitudinally therein, toward and from the rolls 2 and 3. Any suitable means may be used for moving the carriage back and forth, the drawings show a typical lathe carriage movement, comprising a rack 22 on the carriage engaged by a pinion 23 on a transverse shaft 24 mounted in the main frame and provided on its outer end with a hand wheel 25.

In the use of the apparatus described a cup-shaped blank, formed in any suitable way and preferably given a sufficient flare 100 to allow both conical rolls 2 and 3 to enter the same, is secured to the disk 16 while the carriage 20 is in retracted position. The carriage 20 is then moved forwardly to move the blank over the ends of both rolls 2 and 3 which will be in their positions of closest approximation, as shown in full lines in Fig. 1. A relative rotary motion will then be imparted to the blank and the rolls, the drawings showing the rotary motion imparted to the blank by rotating the disk 16 as above described. This rotary motion of the blank also causes the rolls 2 and 3 to rotate, by frictional contact with the inte-

rior of the blank, and to insure freedom of rotation of the rolls 2 and 3 their bearings 4 and 4^a preferably will be of the anti-friction type. The movement described produces a rolling spinning action which expands the cup-shaped blank and thins its walls. The roll carriers 5 and 5^a are caused to slowly separate, by the gearing above described, thus changing the angular positions of the roll shafts and gradually increasing the flare of the cup, until finally its walls are flared out as a substantially flat disk, against the face of the rotary disk 16, as indicated by the dotted line positions of the rolls 2 and 3 in Fig. 1. Inasmuch as the walls of the cup will be expanded to their greatest extent at the open end of the cup, and the amount of expansion decreases gradually and uniformly toward the bottom 20 of the cup, where it is zero, the finished disk will be of uniformly and gradually decreasing thickness or taper from that portion which forms the bottom of the cup blank to the periphery of the disk. The action 25 producing this is a rolling spinning action, tending to expand the walls of the cup circumferentially only, there being substantially no flow of the metal in a direction radially of the completed disk. Consequently 30 the size of the finished disk can be accurately regulated by forming the cup so that its depth plus one-half of its diameter is equal to one-half the diameter of the finished disk. The finished disk can be given 35 such taper that the cross sectional area on any circle outside of the portion which forms the bottom of the cup-shaped blank will be equal to that of any other circle. Since there is no movement of the metal 40 radially of the finished disk, there is no tendency of the metal to form into waves, and no strains produced which would tend to cause radial cracks from the periphery of the disk.

The details of the apparatus described 45 may be varied within wide limits. In a machine where a large output is sought, automatic mechanism may be used in place of the hand wheel 13 for varying the angular positions of the roll carriers and for rapidly bringing the roll carriers back to normal position at the completion of the rolling of a blank, and also suitable power mechanism, such as an air or hydraulic cylinder, may be substituted for the rack and pinion mechanism illustrated for moving the carriage 50 back and forth, in order to secure a quicker movement where speed is desired.

I claim:

1. In an apparatus for converting metallic cup-shaped blanks into disks, the combination of a rotary disk or plate on which the cup-shaped blank is held by its bottom, a conical roll entering said blank from its open end, means for imparting relative rotary movement to said disk and roll respec-

tively, and means for changing the angular relation of the axes of said roll and said disk respectively.

2. In apparatus for converting metallic cup-shaped blanks into disks, the combination of a disk or plate on which the cup-shaped blank is held by its bottom, a pair of conical rolls entering said blank from its open end, means for imparting relative rotary movement to said disk and rolls respectively, and means for progressively increasing the angle between the axes of said rolls.

3. In apparatus for converting metallic cup-shaped blanks into disks, the combination of a rotary holder to which the cup-shaped blank is secured by its bottom, rotary spinning means entering said cup-shaped blank and bearing against the wall thereof, and means for moving said rotary holder and spinning means relative to each other to impart the greatest spinning action to said cup-shaped blank at its open end and gradually decreasing toward its bottom.

4. In apparatus for converting metallic cup-shaped blanks into disks, the combination of a rotary blank holder to which the bottom of the blank is secured, a spinning roll adapted to enter the cup-shaped blank, means for progressively changing the angle of the axis of the spinning roll relative to the axis of the blank holder, and a carriage movable toward and from the spinning roll and provided with bearings for the rotary blank holder.

5. In apparatus for converting metallic cup-shaped blanks into disks, the combination with a pair of conical spinning rolls, bearings in which the same are rotatably mounted, a rotatable blank holder to which the cup-shaped blank is secured by its bottom, a carrier for said blank holder movable toward and from the spinning rolls to carry the cup-shaped blank over said spinning rolls, and means for progressively increasing the angular relation between the axes of the spinning rolls.

6. In apparatus for converting metallic cup-shaped blanks into disks, the combination of a rotatable blank holder to which the cup-shaped blank is secured by its bottom, of a pair of conical spinning rolls arranged to enter said blank from its open end, carriers in which said spinning rolls are rotatably mounted, said carriers being pivoted on axes located close to the position of the plane of the bottom of the cup-shaped blank, and means for progressively moving said roll carriers in opposite directions.

In testimony whereof, I have hereunto set my hand.

ARNOLD CHRISTIANSON.
